UNITED STATES PATENT OFFICE.

JOHN H. LASKEY, OF BOSTON, MASSACHUSETTS, ASSIGNOR OF TWO-THIRDS
TO ISAAC F. DOBSON, OF SAME PLACE, AND BENJAMIN F. DAVIES, OF
CAMBRIDGE, MASSACHUSETTS.

MANTEL-BED.

SPECIFICATION forming part of Letters Patent No. 314,032, dated March 17, 1885.

Application filed March 24, 1884. (No model.)

To all whom it may concern:

Be it known that I, JOHN H. LASKEY, a citizen of the United States, residing at Boston, in the county of Suffolk and State of Massachusetts, have invented certain new and useful Improvements in Mantel-Beds; and I do hereby declare that the same are fully described in the following specification and illustrated in the accompanying drawings.

10 The object of my invention is to improve mantel-beds—that class of beds arranged to turn up on edge against a wall.

My improvements relate to the suspension of the bed-frame by swinging bars to rear and bottom supports therefor working in grooves in the inclosing-case, and to peculiar folding front legs whereby the opened bed is in part supported.

15 My invention consists in the devices and combinations of devices set forth in the appended claims.

In the drawings, Figure 1 is a perspective view of my improved bed spread or opened for use. Fig. 2 is a transverse vertical section of the case, showing the end of the frame and illustrating the various features of my invention. Fig. 3 is an end view of the case, indicating in dotted lines the position of the parts when folded. Fig. 4 is an elevation of 20 one of my improved beds, showing the case closed. Fig. 5 is an enlarged detail of the folding leg. Fig. 6 is a front view of one of the legs and a part of the frame.

A is the case in which the bed is inclosed when folded, the top forming a horizontal shelf or mantel, M, projecting as desired, the casing being plain or suitably ornamented.

B is the bed-frame, the bottom of which closes the front of the case when folded, owing 35 to the peculiar hinging, while the sides and ends fit closely within corresponding parts of the case, leaving merely room at the ends for the supporting devices.

My bed-frame is not, like former ones, mounted on a fixed pivot, but receives a swinging support from two slotted metallic links or 40 hinges, C, each pivoted at one end to the end piece of the folding frame at a point just back of its center, and supported at the other end 45 by a pin, D, fixed in the end wall of the case

and working in a slot in the link. These parts are designed, mainly, to support the bed and its frame during the operations of opening and closing the same, and to give an easy swinging movement while the normal supports are not operative. They serve also, in connection with the guides and without any counter-balance, to maintain the bed when spread at the proper distance from the floor and from the rear of the case, and when folded 55 to bring the frame into the precise position to close the front of the case.

The weight of the bed and frame when folded is borne by two knobs or rollers, E, projecting from the ends of the frame, and having a rest, g, in the bottom of oblique grooves G, formed in the adjacent inner faces of the casing. Such points of rest are near the front lower corners of the case ends, and the rollers E are located at the lowermost corner of the 60 frame ends, as shown, so that when folded the entire front of the case is closed by the bottom of the bed-frame, and the center of gravity is back of the point of support, thus tending to prevent accidental opening of the bed. The 65 front of the case or frame is also provided with a lock and key of approved construction, thus securing the bed against unauthorized use.

The bed is preferably of woven or interlinked wire suspended horizontally from the ends of 70 the frame B and supporting a suitable mattress.

The rollers E give a firm support to the back side of the bed when spread for use. During 75 the operation of opening, these rollers move upwardly and rearwardly in the grooves G as guides until the upper ends thereof are reached and the rollers enter rests or offsets g', so shaped with relation to the guiding portion of the groove as to form rests to retain the rollers 80 until the frame is drawn slightly forward and lifted up to its front edge. This action does not occur in the use of the bed, and the natural tendency of the parts as I have arranged them is to keep the rollers in the recesses g'. 85

The front side of the bed receives its support when open from two folding legs, H, pivoted to the outer ends of the frame B, and yet so constructed as to be very firm and to sus- 90

tain the weight of the bed and its occupant without strain on the pivots of the legs, and to provide for folding them compactly.

Each leg is formed at its upper end with a three-way slot, *h*, through which passes the pivot *I*, by which it is secured loosely to the end of the frame. The upper part of the leg curves sharply outward from this slotted end, and then inward, so as to bring the knee *K* beneath the bottom of the opened frame, near its end. This knee has a cushion, of rubber, leather, or felt, to prevent noise and injury to the frame. From the knee downward the leg is nearly or quite straight, and the weight borne by the legs comes mainly upon the cushion and lower part of the leg, and not largely upon the pivots *I*.

The legs fold between the ends of the folding frame and those of the upright case, and the slots *h* permit this by enabling each leg, when the front of the bed is slightly raised, to drop down until the pivot *I* is in the upper part of the slot, when the knee *K* can clear the lower outer corner of the frame *B* and the leg swing outward and around into the position indicated by dotted lines in Fig. 5, when the rearward portion of the three-way slot permits the neck of the pivot *I* to enter it and allows the leg to fold more compactly.

Between the mantel *M* and the space into which the bed folds I provide with my narrow beds drawers or a shelf, *N*, with a hinged

door, *L*, in front of it. This inclosure affords space for storage of pillows, bedding, or other articles.

35

I claim as my invention—

1. The combination, with the casing having guide-grooves closed at each end, the lower end abutments thereof forming rests, of the bed-frame having projections which enter the grooves, and the links *C*, pivoted at one end to the casing and at the other end loosely pivoted to the frame, substantially as described. 40

2. The combination, with the casing and bed-frame pivoted thereto, of the legs *H*, 45 loosely pivoted to the sides of the frame, said legs having offset-knees *K*, forming a projection to engage with the frame when frame is turned down, substantially as stated.

3. The combination, with the casing and 50 bed-frame pivoted thereto, of the legs *H*, having three-way slots in their upper ends, a pivot passing loosely through said slot, said legs curving back from the pivot and then curving forward, and being provided with the 55 cushioned projection *K*, all substantially as described.

In testimony whereof I hereto affix my signature in presence of two witnesses.

JOHN H. LASKEY.
